UNITED STATES PATENT OFFICE.

THOMAS E. WHITE, OF ROCHESTER, NEW YORK.

TOBACCO-PIPE.

SPECIFICATION forming part of Letters Patent No. 695,185, dated March 11, 1902.

Application filed February 12, 1901. Serial No. 47,033. (No model.)

To all whom it may concern:

Be it known that I, THOMAS E. WHITE, a citizen of the United States, and a resident of Rochester, in the county of Monroe and State 5 of New York, have invented certain new and useful Improvements in Tobacco-Pipes, of which the following is a specification.

My invention relates to tobacco-pipes, and has for its object the admission of air to the 10 bowl that contains the tobacco in such a manner that complete combustion of the tobacco is secured and the smoke is cooled before it reaches the mouth.

Another object of my invention is to secure 15 the drainage of all nicotin and condensed products from the tobacco-bowl and the deposits thereof in a position from which it will not be conveyed to the mouth.

Other objects and advantages besides those 20 I have mentioned will be disclosed in the course of the specification that follows.

In the drawings, Figure 1 is a perspective view of my improved pipe. Fig. 2 represents a vertical section of the bowl, and Fig. 3 represents an elevation of the inner bowl.

The pipe has an outer bowl A and an inner bowl B. The outer bowl may be of any desired shape and has within it and at or near its rim an annular projection or ring a. I 30 have shown this ring as having a thread upon its inner surface. The inner bowl B is smaller than the outer bowl A, so that there is a space C between said bowls that extends up to the ring a. The bowl B has a flange b upon its 35 top, which is adapted to lie upon and project above the top of the bowl A, and thus prevents the insertion of the inner bowl too deeply into the outer bowl. Below the flange b the bowl B is threaded to correspond with 40 the thread upon the ring a.

I have found that in pipes heretofore constructed only the center of the tobacco near the top edge of the pipe is consumed, for the draft is through the center of the pipe, and 45 combustion consequently takes place mainly through the center and imperfectly or not at all against the side of the bowls. To overcome this defect, I have made a series of perforations b' through the flange b on the inner 50 bowl B. The air is directed through these perforations to all parts of the top of the bowl

and complete combustion at this point results. Below the flange b I have also made several series of perforations b² b³ b⁴ in the bowl B. The purpose of these perforations 55 is to produce complete combustion of the tobacco in the bowl below the flange and also to improve the draft. The air enters the bowl B from the top and through the perforations b' and taking the course of least resistance passes down through the tobacco and out through the series of perforations b², that lie next below the ring a into the space C between the two bowls, thus causing a draft toward the sides of the inner bowl. The layer 60 of tobacco that lies above these perforations b² will thus in turn be completely consumed. If when the tobacco has been consumed above the perforations b² it is found that air cannot be drawn through the next lower series of 65 perforations b³ because of the freer passage open to it through the perforations b², the inner bowl B is drawn out from the outer bowl (by unscrewing it, as in the form shown) until the ring a is brought over the series of perforations b², so as to prevent the passage of air 70 through them. When this has been done, it will be found that the air will pass down through the tobacco and out through the perforations b³ and b⁴ and that the combustion of 75 the lower strata of tobacco will be as complete as it was in the case of the upper strata. The number and position of the perforations may of course be varied and the construction of the bowls may be modified without departing from 80 the spirit of my invention. It is also obvious that instead of the thread upon the ring a and the bowl B other means for supporting the bowl B in its adjusted position may be employed.

The large number of perforations through which the air is conveyed to the space between the bowls insures the passage of a considerable quantity of cool air, which, mixing with the smoke in the space between the 85 bowls, cools it before it passes to the mouth. Again, from the fact that the smoke and air are not drawn through the center of a very hot part of the pipe in their passage to the stem, as they are in other pipes, they are less 90 heated than they are in other pipes. Any saliva that may pass into the pipe through 95 100

the stem D will be received in the space C between the bowls, from which it can be easily removed.

Another advantage that results from the peculiar construction of my pipe is that the tobacco in the bowl B does not become saturated or moist by the distillation of the tobacco or by the condensation of the vapor in the highly-heated air that enters the bowl, and also the moisture from the mouth cannot be absorbed by the tobacco. I find after having given my pipe very thorough use that the tobacco in the bottom of the bowl B is never wet, and that whatever moisture is deposited in the pipe is always found in the space C near the ring a, and that a pipeful of tobacco is burned completely to a clear ash.

What I claim is—

1. In a tobacco-pipe, the combination of an outer bowl, a smaller bowl adjustable within the outer bowl and adapted to leave a space between such bowls, and having transverse perforations through its walls throughout its

length, the rim of the outer bowl fitting the inner bowl, and adapted to cover perforations 25 in the inner bowl when said inner bowl is elevated, substantially as described.

2. In a tobacco-pipe, the combination of an outer bowl, imperforate except for a stem connection; a ring within the outer bowl, extending down from the rim of said bowl; a smaller bowl adjustable within said ring and adapted to leave a space between said bowls, said inner bowl having transverse passages through its side walls leading from its interior to said space between said bowls; and a stem connection communicating with said space between said bowls, whereby air and smoke pass from the inner bowl through said passages into said space and thence to and 40 through the stem connection, substantially as described.

THOMAS E. WHITE.
